CLAIM

The ornamental design for a brew bottle, as shown and described.

DESCRIPTION

1. Brew bottle
- 1.1 : Perspective
- 1.2 : Front
- 1.3 : Back
- 1.4 : Left
- 1.5 : Right
- 1.6 : Top
- 1.7 : Bottom
- 1.8 : Perspective

This is a new, original and ornamental design for a brew bottle, reference being made to the accompanying drawings, forming a part thereof in which: fig. 1.1 is a perspective view of a brew bottle showing our new design; fig. 1.2 is a front view thereof; fig. 1.3 is a rear view thereof; fig. 1.4 is a left side view thereof; fig. 1.5 is a right side view thereof; fig. 1.6 is a top view thereof; fig. 1.7 is a bottom view thereof; and fig. 1.8 is second perspective view showing the brew bottle.

1 Claim, 8 Drawing Sheets
